(57) **CLAIM**

I claim the ornamental design for a magnetic block, as shown and described.

DESCRIPTION

FIG. 1 is a front perspective view of magnetic block, containing a top, middle and bottom piece.
FIG. 2 is a front view of the magnetic block of FIG. 1.
FIG. 3 is a rear view of the magnetic block of FIG. 1.
FIG. 4 is a side view of the left side of the magnetic block of FIG. 1.
FIG. 5 is a side view of the right side of the magnetic block of FIG. 1.
FIG. 6 is a top view of the magnetic block of FIG. 1.
FIG. 7 is a bottom view of the magnetic block of FIG. 1.
FIG. 8 is a front perspective exploded view of the magnetic block of FIG. 1.
FIG. 9 is a perspective view of the top piece of the magnetic block of FIG. 8, shown separately for clarity of illustration.
FIG. 10 is a top view of the magnetic block of FIG. 9.
FIG. 11 is a bottom view of the magnetic block of FIG. 9.
FIG. 12 is a front view of the magnetic block of FIG. 9.
FIG. 13 is a rear view of the magnetic block of FIG. 9.
FIG. 14 is a side view of the left side of the magnetic block of FIG. 9.
FIG. 15 is a side view of the right side of the magnetic block of FIG. 9.
FIG. 16 is a perspective view of the top piece of the magnetic block of FIG. 8, shown separately for clarity of illustration.
FIG. 17 is a top view of the magnetic block of FIG. 16.
FIG. 18 is a bottom view of the magnetic block of FIG. 16.
FIG. 19 is a front view of the magnetic block of FIG. 16.
FIG. 20 is a rear view of the magnetic block of FIG. 16.
FIG. 21 is a side view of the left side of the magnetic block of FIG. 16.
FIG. 22 is a side view of the right side of the magnetic block of FIG. 16.
FIG. 23 is a side view of the left side of the middle piece of the magnetic block of FIG. 8, shown separately for clarity of illustration; and,
FIG. 24 is a side view of the right side of the middle piece of the magnetic block of FIG. 8.

1 Claim, 9 Drawing Sheets
